(57) CLAIM

The ornamental design for a foot rest for a weight rack, as shown and described.

DESCRIPTION

FIG. 1 is a top, front, right perspective view of a foot rest for a weight rack showing our new design;

FIG. 2 is a top, rear, right perspective view thereof;

FIG. 3 is a front view thereof;

FIG. 4 is a rear view thereof;

FIG. 5 is a left side view thereof;

FIG. 6 is a right side view thereof;

FIG. 7 is top view thereof; and,

FIG. 8 is a top, front, left perspective view thereof, with the foot rest for a weight rack shown in example environment.

The broken lines immediately adjacent to the shaded areas define the bounds of the claimed design and form no part thereof. The broken lines depicting the remainder of the article show features that form no part of the claimed design. The example environment shown in broken lines in FIG. 8 forms no part of the claimed design.

1 Claim, 8 Drawing Sheets
